(57) **CLAIM**

The ornamental design for a refrigerator, as shown and described.

DESCRIPTION

FIG. 1 is a front perspective view of the refrigerator showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a partial enlarged view of the region 8 taken from FIG. 1;

FIG. 9 is a partial enlarged view of the region 9 taken from FIG. 1; and,

FIG. 10 is a perspective view showing the design in a state of use with the front panel removed for clarity.

The broken lines depict portions of the refrigerator that form no part of the claimed design. The long dash-short dash-long dash broken lines on FIGS. 1, 8 and 9, taken from FIG. 1, and form no part of the claimed design.

1 Claim, 10 Drawing Sheets
